UNITED STATES PATENT OFFICE.

HENRY C. ROSE AND THOMAS J. THOMPSON, OF LEADVILLE, COLORADO.

THILL-COUPING.

SPECIFICATION forming part of Letters Patent No. 449,235, dated March 31, 1891

Application filed August 4, 1890. Serial No. 360,884. (No model.)

To all whom it may concern:

Be it known that we, HENRY C. ROSE and THOMAS J. THOMPSON, citizens of the United States, residing at Leadville, in the county of 5 Lake and State of Colorado, have invented certain new and useful Improvements in Thill-Couplings; and we do hereby declare the following to be a full, clear, and exact description of the invention, such as will enable others 10 skilled in the art to which it appertains to make and use the same.

This invention relates to an improvement in thill-couplings; and the object sought to be accomplished is to produce a more strong, durable, and compact arrangement of parts than 15 has hitherto been known, but at the same time to so construct and assemble the parts that the shafts can be readily and conveniently uncoupled when their detachment from 20 the vehicle is desired.

A further object is to arrange more efficient anti-rattling devices than those heretofore used.

With these ends in view our invention consists in certain peculiarities of construction and combinations of parts, more fully described hereinafter, and pointed out in the 25 claims.

Referring to the accompanying drawings, 30 Figure 1 represents a perspective view of our complete arrangement, showing the parts in coupled adjustment; Fig. 2, a similar view showing the parts uncoupled; Fig. 3, a sectional view taken through line xx of Fig. 1; 35 Fig. 4, a detail of one of the locking-sleeves, and Fig. 5 a detail view of one of the draw-irons.

The reference-letter A indicates the clip by which the coupling-piece is secured to the 40 axle, and B a thick cross-bar formed integral with said clip at the front side of the same, and from the opposite ends of this bar B extend the draw-irons C, which are also formed integral with the bar and clip and project 45 parallel with each other, being connected at their lower portions by a cross-piece D, forming a shoulder d , as seen more clearly in Fig. 2. The outer ends of the draw-irons are made substantially circular, and from their inner 50 adjacent faces extend circular projections or blocks E of less diameter than said draw-iron ends, and therefore leaving annular shoul-

ders c on the inner faces of the latter. The circular boxes E are each provided with vertical recesses or depressions e , which open out 55 of the top of said boxes, but do not extend back their full width to the inside surface of the draw-irons.

The cylindrical head F of the thill-iron G fits between the two boxes E, and the trunnions H, projecting from its opposite ends, are contained in the bottoms of the vertical recesses e at the center of said boxes, and these recesses thus form sockets or bearings for 60 said trunnions. It will thus be seen that the 65 thill-iron is free to turn, but is allowed no sidewise motion, and to prevent rattling of the parts and vertical movement of the trunnions small blocks of rubber I are introduced into the upper end of the recesses or grooves 70 e , and are of such form that they fit snugly over the trunnions and come flush with the outside surface of the boxes. On the latter are fitted circular sleeves or rings J, having the same width as said boxes and fitting 75 snugly up against the shoulders c . These sleeves or bands are free to turn upon the boxes, and are provided with openings j , which are arranged to exactly register with the vertical recesses e , and do not extend entirely across the bands, but leave a connecting-strip k . These sleeves are turned by 80 means of ribs m , formed on their outside surfaces immediately back of the openings j , and these ribs are extended to form lugs n , projecting over the curved surfaces of the draw-irons and traveling around the same.

The operation of coupling and uncoupling will be apparent from the foregoing description and might be stated as follows: The loose, 90 sleeves J are turned until their openings j register with the vertical depressions e of the circular boxes E, and when brought to this position the lugs n will be fitting against the straight surfaces of the draw-irons back of 95 their circular heads, and thus will prevent farther backward movement of said sleeves. After the cylindrical head F of the thill-iron has been introduced between the blocks and sleeves and the trunnions H pushed down 100 through the openings j and into their sockets e the "anti-rattlers" I are inserted and the sleeves turned over them, thus closing the recesses e and confining the trunnions therein.

- The sleeves are carried around until the ribs or lugs *n* abut against the shoulder *d*, formed by the cross-bar *D*, when their openings *j* will be covered by the latter and entrance of dirt, &c., prevented. When in this position it will be seen that the parts assume a compact adjustment, and that accidental uncoupling is almost impossible, but that by turning back the sleeves the thill can be readily detached.
- 10 We provide an anti-rattler for insertion between the thill-iron head and the cross-bar *B*, connecting the rear ends of the draw-irons, and it consists of a rectangular block of rubber *R*, having thickened upper and lower edges *S S'*. This rubber is applied before the sleeves *J* are fitted on the circular boxes or blocks by inserting it between said blocks and the bar *B* and pushing it down until its lower thickened portion *S'* passes the lower surface of the bar *B*. The inside surface of the latter is made somewhat concave, so that when the sleeves are fitted on they will press the central portion of the rubber back into said concavity. Thus it will be evident that the rubber block cannot fall out or become detached in any way accidentally, as the projections formed by its thickened upper and lower edges inclose the bar *B*, and the central portion is kept snugly up against the inner side face of the bar by the sleeves and thill-iron head.
- Having thus described our invention, what we claim as new, and desire to secure by Letters Patent, is—
- 35 1. In a thill-coupling, the combination of the draw-irons, blocks or boxes projecting from their inner adjacent faces and provided with open recesses or depressions, the thill-iron arranged to fit between said boxes, trunnions on said thill-iron adapted to be contained in said recesses, and loose sleeves fitting over said boxes and provided with openings adapted to register with the recesses in the latter, and arranged to be turned to close said recesses, as set forth.
- 40 2. In a thill-coupling, the combination of the draw-irons, blocks projecting from the adjacent faces of the same and provided with open recesses, the thill-iron arranged to fit between said blocks, trunnions on said thill-iron fitting in said recesses, loose sleeves arranged on said blocks and provided with openings to register with the recesses in the blocks, and limiting-lugs on said sleeves, which also serve as means for turning the latter, as set forth.
- 45 3. In a thill-coupling, the combination of the draw-irons, blocks projecting from the adjacent faces of the same and provided with open recesses, the thill-iron having trunnions fitting said recesses and finding bearings therein, rubber blocks in said recesses above the trunnions, and loose sleeves fitting over said blocks and provided with openings adapted to register with the recesses of the blocks, said sleeves arranged to be turned to close said recesses, as set forth.

4. In a thill-coupling, the combination of draw-irons connected by a suitable cross-bar, projections from the adjacent faces of said draw-irons having recesses, a rubber block arranged to be inserted between said projections, and the cross-bar connecting the draw-irons, and being formed with thickened upper and lower edges projecting over the upper and lower surfaces of said cross-bar, respectively, loose sleeves fitting on said projections from the draw-irons and bearing against said rubber block, and the thill-iron having trunnions, which find bearing in the recesses of said draw-iron projections, as set forth.
- In testimony whereof we affix our signatures in presence of two witnesses.
- HENRY C. ROSE.
THOMAS J. THOMPSON.
